UNITED STATES PATENT OFFICE.

PERLEY R. GLASS, OF BROOKLINE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

DUPLEX FASTENER-SETTING MACHINE.

1,381,180.

Specification of Letters Patent. Patented June 14, 1921.

Application filed May 24, 1916. Serial No. 99,556.

To all whom it may concern:

Be it known that I, PERLEY R. GLASS, a citizen of the United States, residing at Brookline, in the county of Norfolk and State of Massachusetts, have invented certain Improvements in Duplex Fastener-Setting Machines, of which the following description, in connection with the accompanying drawings, is a specification, like reference characters on the drawings indicating like parts in the several figures.

This invention relates to duplex machines for setting eyelets, hooks or similar fasteners. Its general object is to provide an improved machine of the duplex type which may be run at high speed with little inertia and which shall be powerful and accurate in its operation.

An important feature of the invention consists in a double-ended tubular punch arranged to be disposed between the two pieces of material in which the fasteners are to be set, in such manner that the material may be perforated by being forced upon the opposite ends of the punch. As herein shown the double-ended punch has concentric upsetting surfaces formed thereon against which the eyelet barrels are clenched. This construction embodies for the first time in a machine of the duplex type the combined tubular punch and upsetting tool which has been used heretofore with great success in single eyelet setting machines, such for example as that of Letters Patent of the United States No. 1,228,768, granted June 5, 1917, upon my prior application.

Another feature of the invention consists in a movable punching plate having a surface extended transversely in the direction of feed so that the location of the coöperating punching tool may be varied while remaining within the range of the plate as the extent of feeding movement is changed. Such construction is advantageous in that it eliminates the necessity for transversely shifting one of the punching members, as is the case with a punch and die construction, and also obviates the difficulty heretofore encountered in preserving an accurate alignment of the members.

Another feature of the invention consists in work guiding means arranged for adjust-

ment to correspond to the variable initial positions occupied by the feeding member when adjusted for different lengths of feed. 55 As herein shown the double-ended punch is utilized to feed the work, being operated by spacing mechanism controlled by a hand lever. The work guiding means are connected to this lever and so moved by it as to 60 occupy a predetermined relation to the punch regardless of its initial position. The operation of presenting the work properly to the machine is thus facilitated and made uniform for all spacings of the feed. 65

These and other features of the invention will be best understood and appreciated from the following description of a preferred embodiment thereof selected for purposes of illustration and shown in the accompanying drawings in which:

Fig. 1 is a view of the machine in side elevation;

Figs. 2, 3 and 4 are views on an enlarged scale illustrating successive steps in the 75 punching and setting operation;

Fig. 5 is a view of the machine in front elevation;

Fig. 6 is a view in perspective of the tool holder and its operating mechanism; 80

Fig. 7 is a view in perspective of the work guiding means and associated mechanism;

Fig. 8 is a sectional view of a portion of the tool holder showing the double-ended 85 punching and upsetting tool;

Fig. 9 is a view in perspective of the punching plates and their operating mechanism;

Fig. 10 is a view in perspective of the setting dies and their operating mechanism; 90

Fig. 11 is a view in perspective of the raceway operating mechanism;

Fig. 12 is a sectional view of one of the shafts upon which the punching plate and 95 setting die levers are mounted;

Fig. 13 is a detail view showing the means for adjusting one of the punching plate operating levers; and

Fig. 14 is a detail view of the connection 100 between the punching plate plungers and their operating levers.

Before proceeding to a description in detail of the various parts of the machine,

it will be convenient to refer briefly to the principal operative parts and their general mode of operation.

The machine is arranged to receive two pieces of material, such as the quarters of an upper, presented on opposite sides to a double-ended punching-and-upsetting tool 40. The two pieces of material are perforated simultaneously by being forced upon the opposite ends of the tool 40 by punching plates 70. After the punching operation and before withdrawing the punches from the holes in the work the tool 40 is moved transversely feeding the holes in the work into alignment with oppositely disposed setting dies 100. The dies are then advanced to insert a pair of eyelets simultaneously and clench the barrels against the upsetting surface which is formed at the base of each punching portion of the tool 40. The setting dies are then retracted and the work stripped from the ends of the tool 40 so that the latter may be returned to its initial position in readiness for a new cycle of operations.

The machine frame 2 is provided with journals for a main shaft 20 carrying upon one end a driving pulley 3 which may be engaged or disengaged with respect to the shaft 20 through clutch mechanism of any suitable character. A treadle rod 16 is shown herein, but other details of the clutch mechanism are omitted for the sake of clearness since they form no part of the present invention. The frame is provided with an upwardly extending yoke-shaped portion 4, in which are mounted the upper operating levers which will be presently described, and with two forwardly extending heads 6 and 8 in which are formed longitudinal bearings for the plungers of the punching plates and setting dies.

A tool holder 42, best shown in Fig. 6, is detachably secured to an arm 48 extending forwardly from a sleeve 50 journaled to oscillate upon a shaft 52 mounted in a stationary portion of the machine frame. Near its outer end the tool holder 42 is provided with a socket to receive the punching-and-upsetting tool 40. This tool is best shown in Figs. 2 to 4 and 8 and comprises a double-ended tubular punch provided with an annular upsetting surface 41 at the base of each punching portion. It is also provided with a transversely extending opening 43 through which may be discharged the punchings which are forced inwardly through the bore of the tubular punches. The tool 40 is retained in the tool holder 42 by a screw 44 threaded into the end of the tool holder as shown in Fig. 8 and entering a socket in one side of the tool 40. The tool holder is tapered at its outer end and provided with a spring U-shaped stripping device 46. Each arm of the stripping device

is perforated and surrounds one of the outer ends of the punching tool.

The tool holder 42 is oscillated to feed the work, as will presently appear, by mechanism which will now be described. The sleeve 50 above mentioned is provided at its lower end with an outwardly extending arm 54 which is pivotally connected to link 56. The link 56 is in turn connected to a second link 58 pivotally mounted by a pin 60 on one end of a reciprocating carriage 62. The carriage 62 is arranged to move from front to rear in guideways formed in the machine frame and is provided with downwardly extending arms 55 which embrace an operating cam 66 on the shaft 20. This mechanism is best shown in Fig. 6 from which it will be apparent that the reciprocating motion of the carriage 62 is transmitted through the mechanism above described to the tool holder 42 as an oscillatory movement.

The extent of the feeding movement transmitted to the tool holder 42 is regulated by a radius link 64 connected to the pivotal point of the links 56 and 58 and having a normally stationary but adjustable point of connection with the machine frame. As shown in Fig. 7 the radius link is connected by a stud 65 to a movable member 67 arranged to swing about the axis of its shaft 69 journaled in the machine frame. The member 67 is provided with a spacing lever handle 63 which is arranged to swing over a stationary segment plate 61 on the machine frame and to be held in any desired adjusted position by pins set in the segment plate. It will be noted that when the lever 63 is set in the position shown in Fig. 5 the path of movement of the connection between the links 56 and 58 will coincide in its general direction with the direction of movement of the reciprocating carriage 62 so that substantially the entire movement of the latter will be effective in swinging the tool holder and relatively long feeding movements will result. When it is desired to decrease the extent of feeding movement, the lever 63 is swung toward the front of the machine thereby carrying the stud 65 to such a position that the path of the point of pivotal connection between the links 56 and 58 is guided in a direction extending transversely with respect to the movement of the carriage 62 so that only a small component of its movement is effective to feed the work.

In this movement of the spacing lever 63 the links 56 and 58 will be somewhat moved and the initial position of the tool holder 42 will be correspondingly shifted. In the feeding movement, however, the tool holder will be brought always at the end of its movement to position the tool 40 in the same place, viz., in alignment with the setting

dies. The feeding movement of the punching tool therefore takes place between a variable but predetermined initial position and an invariable final position.

5 In order that the spacing lever 63 may be swung by treadle connections without stopping the machine the shaft 69 is provided at its lower end with an outwardly extending arm 59 to which a treadle chain is connected. A spring 57 anchored to a pin on the frame and connected to a portion of the member 67 tends normally to hold the spacing lever 63 at one limit of its movement and the action of this spring is opposed when the treadle connections just described are operated.

The punching operation is effected by simultaneously forcing the two pieces of material upon the ends of the punching tool 40. This is effected by a pair of oppositely disposed punching plates 70 which are carried respectively by plungers 72 mounted for reciprocation in bearings in the stationary heads 6 and 8 of the machine frame. The punching plates 70 have sufficient punching area to include the entire range of adjustment as to the punching position of the double-ended punching tool 40. The punching plates are provided with recesses 30 through which may pass the setting dies 100. When the punching plates are operated the work is forced upon the opposite ends of the punching tool 40, and the arms of the stripper 46 are sprung by the work. The punching plates are then slightly retracted to relieve their pressure upon the punching tool and the feeding operation then takes place. During this operation the work is held upon the ends of the punching tool by the plates 40 70 and the arms of the stripper remain flexed during the feeding operation and also until the setting dies have been operated to engage the work. The punching plates 70 prevent both arms of the stripper from 45 throwing the work off from the punching tool until the setting operation has taken place.

Each plunger 72 is provided at its outer end with a head 73 having an open socket to receive one end of a connecting link 74. The head 73 is provided with an opening to receive a stud projecting from the hub of the link 74. The links 74 are similarly shaped at both ends, and they connect the plungers 55 with operating levers 76 which have sockets similar to those of the heads 73. A leaf spring 75 is secured to each lever 76 and arranged to bear upon the adjoining hub of the link 74 to retain it in its socket in the lever 60 76. When it is desired for any reason to remove a link 74 it is necessary only to loosen the spring 75 and to swing it from the end of the link whereupon the link may be slipped out of its sockets.

65 The upper operating lever 76 is supported

by a pin 78 mounted in the upper part of the yoke portion 4 of the machine frame. An adjustable eccentric bushing is interposed between the pin and the lever as shown in Fig. 9 and affords convenient means for adjusting the pressure of the punching plate operated by this lever. The lower operating lever 76 is correspondingly mounted upon a pin 79 which is set in the machine frame and illustrated in detail in Fig. 12. As 70 shown in this figure the frame is provided at one side with an outwardly extending boss 12 which affords an extended bearing for a bushing 110. The eccentric bushing 77 upon which the lower lever 76 is mounted is 75 provided on its outer end with a recess adapted to receive a corresponding projection on the inner end of the sleeve 80. The sleeve 80 is provided with a head disposed outside the machine frame and provided with 80 openings for a spanner wrench. The eccentric bushing 77 may be turned for purposes of adjustment through the medium of the sleeve 80, the latter being maintained in adjusted position by a nut 81 on the end of the 85 shaft.

The rear ends of the operating levers 76 are connected by a pair of toggle links 82 and 83. At their common pivotal point the toggle links are connected to a slide 84 arranged for movement in a stationary guideway formed in a portion 10 of the machine frame. A link 86 is also connected to the common pivotal point of the toggle links 82 and 83 and this in turn is connected to 90 the upper end of a cam lever 88 journaled to oscillate upon a transverse shaft 22, extending across the rear part of the machine frame. The lever 88 is shaped to embrace an operating cam 90 secured upon the main 95 shaft 20. The cam 90 is so shaped as to swing the lever 88 rearwardly to straighten the toggle links 82 and 83 so as to advance the punching plates 70 to effect the punching operation. The lever 88 is then moved 100 slightly farther toward the rear, thus breaking the toggle links upon the other side of the center line and slightly retracting the punching plates 70. The punching plates are maintained in this position while the 105 feeding operation takes place, and finally the lever 88 is moved forwardly into the position shown in Fig. 9 and brought to rest with the punching plates retracted.

The setting dies 100 are arranged for 110 movement in bearings in the heads 6 and 8 parallel to and at one side of the punching plate plungers 70. Each of the setting dies is connected at its outer end to a link 102, similar to the links 74 above described, and 115 these in turn are connected respectively to the forward end of an upper bell crank lever 106 and a lower bell crank lever 104. The upper lever 106 is mounted upon an eccentric bushing on pin 78 and adjacent to the 120 125 130

upper operating lever for the punching plate plunger. The lower operating lever 104 is mounted upon an adjustable eccentric bushing 107 on pin 79, the bushing being connected to an adjusting sleeve 110 similar to the sleeve 80 and located upon the other end of the pin 79. The inwardly extending arms of the levers 104 and 106 are connected by a short link 108 so that their motion 10 takes place equally and oppositely. The lever 104 has a rearwardly extending arm 112 provided with a curved slot in which is received a correspondingly curved block 114. The block 114 is pivotally connected to a 15 double crank 116 on the shaft 20. This form of operating mechanism for a setting die is disclosed and broadly claimed in my prior application above identified. It has been found particularly satisfactory in im- 20 parting to the dies the movements necessary to take eyelets from the raceways and, upon the withdrawal of the raceways, to advance the eyelet for the setting operation.

The work passes to the tool holder 42 from work guiding means in which the work is preliminarily presented and which will now be described. A guide plate 120 is detachably mounted in an arm 122 extending forwardly from a sleeve 124 journaled upon the shaft 52 beneath the sleeve 50 which carries the tool holder. The arm 122 extends upwardly so that the guide plate 120 is located in the same plane as and parallel to the tool holder 42. A gage block 126 is adjustably mounted on the guide plate 120 and provided with a pair of presser feet each comprising a spring 128 and an end portion 130. The presser feet are similar in construction and disposed upon the upper and lower surfaces of the guide plate 120. They are flared outwardly at their forward ends to facilitate the insertion of the work. Each of the springs 128 is provided with a U-shaped section to accommodate the adjacent portion of the punching plate 70. The guide plate 120 is provided on opposite faces with grooves extending parallel to the direction of feed so that, in handling uppers in which lacing hooks have already been set, the endmost hooks may enter said grooves and be moved close up to the punching tool 40 when it is desired to set an eyelet with a short spacing. The guide plate 120 is also provided with a transversely extending stud 132 arranged to be projected in to the transverse opening 43 of the punching tool and to eject the punchings which have been forced into it. This construction and its manner of operation will be clear from 55 Fig. 4.

As already pointed out, it is desirable to locate the work guiding means in the same relation to the tool holder 42 regardless of the adjusted position of the latter. To this end the sleeve 124 which carries the work

guiding means is provided with an outwardly extending arm 134 which carries a roller 136 at its end. The roller 136 is received in a segmental cam slot formed in the member 67 of the spacing mechanism. The cam slot is so shaped as to oscillate the arm 134 and the work guiding means, when the spacing lever is moved, sufficiently to compensate for any movement of the tool holder produced in adjusting the extent of the feed. 75 Thus, whatever the initial position of the tool holder 42, the work guiding means will be found close beside it so that the presentation of the work will take place in precisely the same manner although at a some- 80 what different position in the machine.

The eyelets are supplied to the setting dies from a hopper 140 through a pair of raceways 144. The raceways are arranged to be moved into delivering position in alinement 85 with the setting dies and, after delivering the eyelets, the raceways are moved outwardly to an inoperative position. To this end the hopper and raceways are mounted upon an oscillating bracket 146 provided with clamping means 148. The bracket 146 is mounted to oscillate between pivot pointed screws 160 and 161 each of which is threaded into an eccentric bushing 150. The bushings 150 are adjustably retained in a pair of ears 147 and 90 149 projecting rearwardly from the machine frame. The bracket 146 has an outwardly extending arm 162 connected through a universal joint to an adjustable link 166 which in turn is connected through another universal joint to a cam lever 168 arranged to oscillate upon the shaft 22 above mentioned. The cam lever 168 is shaped to embrace an operating cam 170 fast upon the main shaft 20. The cam 170 is shaped to oscillate the 105 lever 168 and the raceways in the proper timed relation to the setting dies 100.

In order temporarily to suspend the supply of eyelets means are provided for turning the eccentric bushing 150 to shift the 110 bracket 146 bodily so as to carry the raceways to an inoperative position. To this end the upper bushing 150 is connected to a downwardly extending arm 152 and the lower bushing member (not shown) is similarly connected to an upwardly extending arm 154. The arms 152 and 154 are secured together so that an equal movement of the bushings is insured. The lower arm 154 is provided with an outwardly extending lug 120 through which extends a rod 164. A spring 156 surrounds the rod 164 and bears against the lug on the arm 152, thus normally maintaining the bushings 150 in a position to render the raceways operative. When it is 125 desired to move the raceways to inoperative position it is necessary merely to pull the rod 164 forwardly compressing the spring 156 and turning the bushings 150 as above outlined.

The operation of the machine will be apparent from the foregoing description, but may be briefly summarized as follows: Having adjusted the tool holder 42 and the guide plate 120 to determine the spacing of eyelets by means of the lever 63, the operator presents the two pieces of work upon opposite sides of the guide plate 120 with the point at which the first eyelets are to be set 10 in line with the double-ended punching tool 40. The yielding presser feet 130 maintain the work in the relation to the punching tool which is established by the presentation of the work. The initial position of the operative parts of the machine is well shown 15 in Fig. 2. The machine is then started and the punching plate 72 advanced to force the work upon the opposite ends of the punching tool, the punchings passing into the bore of the tool. This position of the parts 20 is shown in Fig. 3 of the drawings. The punching plates 70 are then slightly retracted and the punching tool 40 is moved transversely into alignment with the setting dies 100, the punching plates serving in the meanwhile to prevent disengagement of the work from the punch. Eyelets have meanwhile been delivered to the setting dies and the dies are next operated to force the eyelet 25 barrels through the holes in the work and to clench their barrels upon the annular upsetting surfaces about the punching portions of the tool. In this operation the punchings are forced by the die spindles into the transverse bore of the punching tool 40. Fig. 4 illustrates the parts of the machine in 30 this position. The setting dies are then retracted and the work thrown off the clenching tool by the stripper 46. The tool holder 42 is then moved toward the right to its initial position and in this movement the pin 132 encounters the punchings and ejects them through the passage 43. At the conclusion of the return movement of the tool 35 holder the machine parts arrive at their initial positions in readiness for the repetition of the cycle.

The various features of the invention have been described above as embodied in a machine of the duplex type in which type of machine they may be employed with particular advantage. Many features of the invention, however, are obviously not limited in their utility to a duplex machine and their 50 employment in a machine of the single type would be within the scope of the invention.

Having thus described my invention, what I claim as new and desire to secure by Letters Patent of the United States is:

60 1. A duplex fastener setting machine having, in combination, a double ended tubular punch, means for forcing the work upon the punch from both ends, and means for presenting fasteners to the holes so formed.

65 2. A duplex fastener setting machine

having, in combination, a double ended tubular punch, means movable toward both ends of the punch for forcing two pieces of material upon the punch, and cooperating fastener inserting devices.

70

3. A duplex fastener setting machine having, in combination, a double ended punch, a punching plate having an extended transverse surface movable simultaneously toward each end of the punch to force two pieces of material upon the punch, and cooperating fastener inserting devices.

75

4. A duplex fastener setting machine having, in combination, a punch holder, a double ended tubular punch set in the holder, a punching plate movable toward or from either end of the punch, and cooperating fastener inserting devices.

80

5. A duplex fastener setting machine having, in combination, a pair of punching plates having extended transverse surfaces and being arranged for movement in aligned paths, a transversely movable punch holder disposed between the punching plates, a double ended tubular punch in the holder, and cooperating fastener inserting devices.

85

6. A duplex fastener setting machine having, in combination, a pair of punching plates having extended transverse surfaces and being arranged for movement in opposite directions, a double ended punch disposed between the plates, means for varying the initial transverse position of the punch, means for moving the punch to a predetermined final position to feed the work, and cooperating fastener inserting devices.

90

7. A duplex fastener setting machine having, in combination, a pair of punching plates arranged for movement in opposite directions, a double ended punch arranged to be disposed between the plates and movable to feed the work, means for changing the initial position of the punch without moving it out of range of the plates, and cooperating fastener inserting devices.

105

8. A duplex fastener setting machine having, in combination, a pair of punching plates arranged for movement in opposite directions, a double ended punch arranged to be disposed between the plates, means for advancing the plates while the punch is located between them, means for moving the punch transversely out of range of the plates, and cooperating fastener inserting devices.

110

9. A duplex fastener setting machine having, in combination, a pair of punching plates arranged for movement in opposite directions, a double ended punch initially disposed between the plates, and means for advancing the plates toward the punch to perforate two pieces of material and then to retract slightly the plates, the double ended punch being moved transversely with

125

130

its ends in close proximity to the plates for feeding the work.

10. A duplex fastener setting machine having, in combination, a pair of oppositely disposed punching plates, a pair of oppositely disposed setting dies located at one side of the plates, an intermediate double ended punch, and means for advancing the plates to perforate two pieces of material in coöperation with the double ended punch, the punch being thereupon moved transversely into line with the setting dies.

11. A duplex fastener setting machine having, in combination, a pair of oppositely disposed punching plates each provided with a recess, a pair of inserting dies disposed in alinement with the recesses, and a double ended punch movable transversely from a position opposite to the faces of the punching plates to a position in line with the recesses thereof.

12. A duplex fastener setting machine having, in combination, a double ended punch, coöperating punching plates, yielding stripping means adjacent to both ends of the punch, and coöperating fastener setting devices.

13. A duplex fastener setting machine having, in combination, a double ended punch, a stripper disposed adjacent to each end of the punch, and means for forcing two pieces of material upon the punch and for depressing the strippers, the punch being moved transversely to feed the material while the strippers are maintained depressed.

14. In a fastener setting machine, a movable tool, a tool operating lever, and means for detachably connecting said tool and said lever comprising a removable stud and displaceable means for normally retaining the stud in connecting position.

15. In a fastener setting machine, a reciprocable tool, a pivoted operating lever, and means for detachably connecting said lever and said tool comprising a removable link having integral stud connections to the lever and the tool and displaceable means for normally retaining the stud and link in connecting position.

16. A duplex fastener-inserting machine having, in combination, a reciprocatory work-feeding member arranged to act on and between two confronting layers of work, and stationary work-guiding means arranged to lie between the layers of the work in advance of said feeding member to guide the work to the latter.

17. A fastener setting machine having, in combination, a feeding member arranged to be moved from a variable initial position to a predetermined final position, and work guiding means located in advance of the feeding member and movable to correspond to the initial positions of feeding member.

18. A duplex fastener setting machine having, in combination, setting devices, a double ended punch movable to feed two pieces of work, means for varying the extent of the feeding movement, and work guiding devices controllably related to said means.

19. A duplex fastener setting machine having, in combination, setting devices, a double ended punch movable to feed two pieces of work, a spacing lever for regulating the extent of feeding movement, and yielding presser feet constructed and arranged to be shifted when the spacing lever is moved.

20. A duplex fastener setting machine having, in combination, a feeding member and guide plate both arranged to be inserted between two pieces of work, and a single device for controlling the movement of the feed member and the position of the guide plate.

21. A fastener setting machine, having, in combination, a feeding member and work guiding member both arranged for movement about a common axis, power operated means for oscillating the feeding member independently of the guiding means, and manually operated means for shifting both of said members.

22. A fastener setting machine, having, in combination, a feeding member and a work guiding member both arranged for movement about a common axis, means for oscillating the feeding member including a pair of transmission links, and manually controlled means for regulating the action of the links and at the same time shifting the guiding member.

23. A fastener setting machine, having, in combination, a feeding member and a work guiding member movable in substantially the same plane, power operated mechanism for oscillating the feeding member, and a regulating lever therefor having a separate train of connecting mechanism to the guiding member.

24. A fastener setting machine, having, in combination, a pair of setting devices, a tubular punch having a transverse opening, a work guiding plate relatively movable with respect to the punch, and means carried by said plate to eject a punching from the transverse opening of the punch during such relative movement.

25. A duplex fastener setting machine, having, in combination, a pair of oppositely disposed setting dies, connected bell crank levers for operating the dies one of which is provided with an arm having a curved slot therein, a curved block arranged to slide in the slot, and a crank for moving the block to swing the levers.

26. A fastener setting machine, having in combination, a pair of setting devices, a tu-

- 5 bular punch, a punching plate having a transversely extended surface, and work guiding means including a presser foot having an offset section to receive a portion of the punching plate.
- 10 27. A fastener setting machine, having in combination, a machine frame having spaced side members, a shaft extending through the frame, punching and setting instrumentalities, operating levers therefor mounted side by side on the shaft, an eccentric bushing for one of the levers, and an adjusting sleeve therefor extending outwardly through the frame.
- 15 28. A fastener setting machine, having in combination, a movable raceway, a bracket therefor, separate pivot members for supporting the bracket, an eccentric bushing for each pivot member, a connecting device extending between the bushings, and means acting on the connecting device for temporarily swinging the bushings.
- 20 29. A fastener setting machine, having, in combination, a combined tubular punching and upsetting tool, a plate having an extended transverse surface movable toward the tool to perforate the work, and a fastener presenting tool arranged to replace the plate in operative relation to the tool.
- 25 30. A fastener-setting machine having, in combination, a work-feeding member and work-guiding means arranged to engage one and the same surface of the work, the feeding member being movable relatively to the guiding means and having a variable range of feeding movement, and the guiding means being adjustable according to a variable limit of said range.
- 30 31. A fastener setting machine having, in combination, a pair of setting devices, a punch movable to feed the work, means for varying the extent of the feeding movement, and a work guiding device relatively to which the punch is movable, said guiding device being adjustable by said means.
- 35 32. A fastener setting machine having, in combination, a pair of setting devices, a punch movable to feed the work, a spacing lever for regulating the extent of feeding movement, and a yielding presser foot constructed and arranged to be shifted when the spacing lever is moved.
- 40 33. A fastener setting machine having, in combination, a feeding member, a member arranged to guide the work as the latter is fed, and a single device for controlling the movement of the feeding member and the position of the guiding member.
- 45 34. A fastener setting machine having, in combination, a work feeding member and a work-guiding member arranged to function conjointly as the work advances, and a single device for controlling the movement of the feeding member and the position of the guiding member.
- 50 35. A machine for setting fasteners, comprising a work-feeding member and stationary work-guiding means arranged to engage one and the same surface of the work, the work-feeding member having a variable range of feeding movement, and the guiding means being adjustable to various positions substantially tangential to a variable limit of said range.
- 55 36. A fastener-inserting machine having, in combination, step-by-step work-feeding mechanism including a reciprocatory work-engaging member, means arranged to regulate the operation of said feeding mechanism so as to vary the length of the feed-steps, a stationary member arranged to guide the work to said work-engaging member, and means operable by said regulating means to vary the position of said guiding member according to variations in the potential feeding capacity of said work-engaging member of the feeding mechanism.
- 60 37. A duplex punch having tapered punch ends and relatively movable anvils simultaneously coöperative with said punch at opposite ends of the punch.
- 65 38. A duplex punch having punch ends and clenching surfaces therearound, an anvil coöperative with each end of said punch, and lifter springs to lift the material off the punch ends as the anvils are retracted.
- 70 39. A duplex punch having sharpened cutting ends and a passage therethrough extending between said cutting ends and having a lateral opening through the side wall of said punch to allow the escape of punchings from said passage.
- 75 40. A duplex punch having cutting ends, movable anvils coöperating with the cutting ends of said punch to force work thereagainst to punch the same, and means for thereafter stripping the work from said punch ends.
- 80 In testimony whereof I have signed my name to this specification.

PERLEY R. GLASS.
